UNITED STATES PATENT OFFICE

2,386,485

SELF-PRIMING CENTRIFUGAL PUMP

Charles I. Longenecker, Wauwatosa, Wis., assignor to Chain Belt Company, Milwaukee, Wis., a corporation of Wisconsin

Application May 17, 1943, Serial No. 487,362

3 Claims. (Cl. 103—113)

The invention relates to pumps, and constitutes a further development of the centrifugal self-priming liquid pump disclosed in my co-pending application Serial No. 444,891 filed May 28, 1942, entitled Pump construction, in which is described and claimed a light-weight centrifugal pump the elements of which are constructed largely of sheet metal and/or standard seamless pipe, which not only are particularly adapted to welding operations whereby they are assembled, but are also relatively less expensive than castings and provide a material reduction in the weight of the pump.

The present invention relates more especially to a suction chamber unit for such a pump, which is likewise constructed of stamped or otherwise suitably shaped elements of sheet metal, plate and pipe sections welded together and supporting or carrying the inlet or suction valve of the pump as well as the valve which automatically controls the flow or recirculation of the priming liquid.

One example of such a chamber and valve unit is illustrated in the accompanying drawings forming a part of this specification, in which like reference characters designate like parts in all the views, and in which

Figure 1 is a side elevational view, partly broken away and in section, of a recirculating self-priming centrifugal pump of substantially the same general construction as that disclosed in my said prior application Serial No. 444,891 but with a suction chamber and valve unit in accordance with the present invention embodied therein;

Fig. 2 is an end elevational view of the parts illustrated in Fig. 1, as seen from the right thereof;

Fig. 3 is a central longitudinal sectional view, on a somewhat larger scale and partly in elevation, of the chamber and valve unit;

Fig. 4 is an end elevational view, partly broken away, of the parts shown in Fig. 3, as seen from the right thereof;

Fig. 5 is a top plan view, also partly broken away, of the parts shown in Fig. 3;

Fig. 6 is a transverse sectional view taken approximately on the planes indicated by the line 6—6 of Fig. 3, looking in the direction of the arrows; and

Fig. 7 is a perspective view of the valve assembly which controls the recirculation of the priming liquid.

Referring more particularly to Figs. 1 and 2, as in my said prior application the pump casing

or body constitutes a delivery and priming water chamber 10, and is formed from a sheet metal annulus 11 to the opposite ends of which the sheet metal heads 12 and 13 are peripherally welded. A sheet metal partition plate 14 and a spiral or volute strip 15 provide an impeller chamber 16 adjacent the head 12, in which chamber is located an impeller 17, carried by a shaft 18. A housing 19 is detachably secured to the head 12 and encloses a suitable seal for preventing escape of the fluid along the shaft 18. A discharge conduit or pipe 20 extends through and is welded to the annulus 11, and a filler conduit 21 also extends through the said annulus to enable the initial introduction of priming liquid into the pump casing. The head 13 is provided with a clean-out opening 22, normally closed by the cover plate 23 which in turn may be provided with a drain passage 24 normally closed by a plug 25.

The partition plate 14 is provided with an inlet port 26 for the impeller chamber 16, and the head 13 is provided with a centrally located opening 27 through which the suction chamber and valve unit 29 of the present invention extends to the said port, as will be clear from Fig. 1.

This unit, the details of which are better shown in Figs. 3-7, comprises a body member 31 of substantially U-shape in cross section, which may be stamped from sheet metal, the open top of which is closed by a sheet metal member 32 edge-welded to the said body member, as indicated at 33, to form a perimetricaly closed suction chamber 30. A flange plate 34 is welded to the outer end of said chamber members, which end is preferably beveled or inclined as will be clear from Figs. 1 and 3, and the central portion of such plate 34 is cut out to provide an inlet port or passage 35 for the chamber. The said plate also serves as a support for the inlet or suction valve of the pump, which comprises a sheet 36 of rubber or equivalent flexible material having a U-shaped cut-out 37 providing a valve tongue 38. This tongue is preferably weighted to assist in biasing it to closed position by a metal plate 39 and washer 40, secured to the tongue by a screw 41.

The perimetric portion of the sheet 36 is clamped between the outer face of the plate 34 and a companion plate member 42 by bolts 43, which latter plate is centrally apertured as at 44 and provides a valve seat 45 against which the perimetric portion of the tongue 38 rests when the valve is in closed position. A short section of pipe 46 is welded to the outer face of the flange

plate 42 and may be threaded as at 47 for connection to the suction or intake line.

By constructing the suction chamber and valve as above set forth, the valve is permitted to swing to an open position—shown in broken lines in Fig. 3—in which the intake port is substantially unobstructed thereby.

Adjacent its inner end the body member 31 is apertured to receive an end of a short pipe section 50, constituting the conduit through which priming liquid may be transferred from the delivery and priming water chamber 10 to the suction chamber 30 when the supply of liquid to be pumped fails, in the manner well understood by those skilled in the art. The pipe section 50 also supports a valve assembly 51, the valve of which automatically controls the flow of priming water through the said pipe in substantially the manner disclosed in U. S. Patent No. 2,217,380 granted October 8, 1940, on an application filed by Frank S. Pedder and myself.

This valve assembly, as will be clear from Figs. 3-7, comprises a supporting arm 52 having an angularly disposed end portion 53 to which is secured as by bolts 54 one end of a resilient tongue or leaf 55 constituting the valve element, there being a rubber pad or equivalent resilient element 49 interposed between the leaf and arm. The leaf is normally straight, as best shown in Figs. 4, 6 and 7, and by reason of its attachment to the angularly disposed end portion 53 of the supporting arm 52, the free end of the leaf normally extends below and in spaced relation to the lower end of the pipe section 50. The end face of the pipe section provides a seat 56 against which the valve leaf may be drawn by the partial vacuum in the suction chamber 30 and the velocity and/or pressure of the priming water entering the pipe 50 from the chamber 10, to cut off the flow of priming water, all in the manner set forth in said prior Patent No. 2,217,380.

The manner of mounting the supporting arm 52 of the valve assembly is somewhat different from that disclosed in the said patent, in that its end 57 is provided with a clamping device 58, here shown as a conventional pipe or hose clamp to which the end portion 51 of the arm is welded. The cylindrical portion of this clamp is slipped upon the pipe section 50, as shown in Figs. 3, 4 and 6 and by means of a bolt 59 passed through the apertures 60 in the ears 61 of the clamp, the valve assembly may be rigidly secured to the said pipe section. This construction not only facilitates the mounting and/or dismounting of the valve assembly, but also provides for easy adjustment of the valve leaf 55 toward or from its seat

56 to secure proper operation and/or maximum efficiency in the functioning of the valve. As will be noted from Fig. 1, the valve assembly is positioned adjacent the clean-out opening 22 in the casing head 13, and the mounting, dismounting and/or adjustment of the valve may be readily accomplished through said opening upon removal of its cover 23.

Having thus described the invention, what is claimed is:

10 1. An intake unit for a recirculating self-priming centrifugal pump having a casing providing an impeller chamber and a priming-liquid chamber: said unit comprising a perimetrically closed sheet metal suction chamber element adapted to extend through a wall of the pump casing for conveying liquid from exteriorly of said casing across the priming-liquid chamber and discharging it to the impeller chamber; a check valve carried by the portion of said suction chamber element exterior of the casing, for preventing back-flow of fluid through said element; a conduit carried by the interior portion of said suction chamber element, for providing communication between it and the priming-liquid chamber; and a valve assembly readily adjustably mounted on said conduit, including a valve for controlling passage of priming-liquid through the conduit to the suction chamber.

15 2. A unit for a recirculating self-priming centrifugal pump, comprising an open-ended perimetrically closed sheet metal suction chamber element for conveying liquid to the pump impeller chamber, said element being provided with an exteriorly extending conduit for admitt'g priming liquid to the suction chamber; a valve co-operable with the intake port of said conduit for controlling the passage of fluid therethrough; and a support for said valve having means for readily detachably and adjustably mounting the support on said conduit, whereby the position of the valve relative to said intake port may be readily varied.

20 3. A unit for controlling the flow of priming liquid through a conduit of a recirculating self-priming centrifugal pump, comprising a resilient valve leaf for seating co-operation with the intake end of the conduit; and a supporting arm to which one end of said valve leaf is secured, said arm having a clamping member rigidly secured thereto and adapted for encirclement of and readily detachable and adjustable securement to the conduit, whereby the position of the valve leaf relative to said end of the conduit may be readily varied.

25 45 50 55 CHARLES I. LONGENECKER.
